US00D952000S

(12) **United States Design Patent** (10) Patent No.: **US D952,000 S**
(45) Date of Patent: **** May 17, 2022**

(54) **ENGINE PART**

- (71) Applicant: **PSG GERMANY GMBH**, Duisburg (DE)
- (72) Inventors: **Andreas Kneer**, Rheinberg (DE); **Sascha Westphal**, Kamp-Lintfort (DE)
- (73) Assignee: **PSG GERMANY GMBH**, Duisburg (DE)
- (**) Term: **15 Years**
- (21) Appl. No.: **29/778,965**
- (22) Filed: **Apr. 15, 2021**

Related U.S. Application Data

- (62) Division of application No. 35/507,027, filed on Dec. 6, 2018 (U.S. filing date under 35 U.S.C. 384), and having an international filing date of Dec. 6, 2018, now Pat. No. Des. 923,060.

(57) **CLAIM**

The ornamental design for an engine part, as shown and described.

DESCRIPTION

FIG. 1 is a perspective view of an engine part;
FIG. 2 is a front view thereof;
FIG. 3 is a back view thereof;
FIG. 4 is a top view thereof;
FIG. 5 is a bottom view thereof;
FIG. 6 is a right side view thereof; and,
FIG. 7 is a left side view thereof.

1 Claim, 7 Drawing Sheets
